METHOD OF MAKING A HEAT EXCHANGER

Arthur B. Modine, Racine, Wis., assignor to Modine Manufacturing Company, Racine, Wis., a corporation of Wisconsin

Application November 25, 1955, Serial No. 548,888

5 Claims. (Cl. 29—157.3)

The invention relates generally to heat exchange structures and more particularly to a fin structure of variable thickness and the method of making the same.

The advantages of a tapered fin structure in heat exchangers are well known and in certain cases such types of fin structures have been utilized, such constructions, however, involving either an integral preformed construction, as for example, a coating or a fabricated construction involving a plurality of assembled elements, as for example, that illustrated in my prior Patent No. 2,339,284 dated January 18, 1944.

The present invention is of particular advantage where the fin members are normally formed from sheet material and operatively associated in heat transfer relation with one or more fluid conducting elements, a typical example of which is the tubular type automotive radiator core having a plurality of parallel fluid conducting tubes connected by a plurality of generally parallel fin members formed from sheet or strip material and extending transversely to the tubes. Fin elements of this type have utilized sheet material of substantially uniform thickness and obviously in such case, the thickness of the material is primarily controlled by that portion of the structure which would require the greatest thickness. In the example of a radiator core, that portion would be adjacent the fluid conducting tubes and may involve consideration of both structural and heat transfer characteristics. Obviously, where a fin structure of uniform thickness is employed, the entire structure is of necessity the maximum thickness required in any portion thereof with a corresponding increase in weight, cost of materials, etc., over what would be required if the unnecessary material could be eliminated.

The present invention has among its objects the production of a heat transfer structure which utilizes a sheet metal fin element of varying thickness, whereby the various portions of the fin element may be of substantially minimum thickness consistent with the operational and functional requirements of such portions.

Another object of the invention is the production of such a fin element which may be readily substituted for prior fin structures whereby the fabrication of such exchangers may employ standard techniques and machinery, etc.

A further object of the invention is the utilization of a novel method forming such fin elements whereby the same may be fabricated from stock of either greater or lesser thickness than the maximum thickness of the formed fin element.

Many other objects and advantages of the construction herein shown and described will be obvious to those skilled in the art from the disclosure herein given.

To this end my invention consists in the novel construction, arrangement and combination of parts herein shown and described and more particularly pointed out in the appended claims.

In the drawings wherein like reference characters indicate like or corresponding parts:

2

Fig. 1 is an enlarged transverse sectional view of a portion of a heat exchange structure embodying the present invention;

5 Fig. 2 is an enlarged longitudinal sectional view of a fin element formed from stock of greater thickness;

Fig. 3 illustrates a novel way in which the element of Fig. 2 may be fabricated;

Fig. 4 is an enlarged view similar to Fig. 2 of a fin element formed from stock of lesser thickness; and

10 Fig. 5 illustrates a novel way in which the element of Fig. 4 may be fabricated.

Referring to the drawings, and particularly Figs. 1, 2 and 3, Fig. 1 illustrates a small portion of a tubular type heat exchange structure, portions of two tubes 1 being illustrated, with the tubes 1 being connected by a plurality of fin elements indicated generally by the numeral 2 and formed from sheet material. In the particular example illustrated, the elements 2 are provided with a plurality of openings 3 through which the respective tubes extend, which openings 3 are defined by flanges 4 struck from the material of the strip originally positioned at the openings 3, forming annular collars which in the example illustrated also may function as spacing means for the strips 2. The portions of the strips 2

15 intermediate the tubes 1 forming the secondary surface of the heat exchange structure vary in thickness from the central portion 5 thereof to the portions 6 adjacent the respective tubes, the thickness suitably increasing from the intermediate portion 5 to the portions 6, thus in effect forming fin structures tapering outwardly with respect to the tubes associated therewith. It will be appreciated that the tapered fin structure provides a maximum heat transfer with a minimum of metal in the fin and a corresponding minimum in weight of the finished

20 structure for the particular operational characteristics and efficiency, as distinguished from prior constructions wherein the fin structures are of substantially uniform thickness, necessitating the utilization of stock having a thickness equal to the maximum required, which in the example given would be the portion 6 adjacent the tubes 1.

Referring to Fig. 2, y represents the distance from the center line of the tube 1 to the beginning of the tapering portion represented by the letter x , so that the portions 6 have a length of $2y$, while the intermediate portions taper from the thickness of the portions y to approximately one-half thereof in a distance equal to one-half of x . The construction illustrated in Fig. 2 may be fabricated in the manner illustrated in Fig. 3 wherein

25 the strip 2 is fed between two rollers 7 and 8, the roller 7 being cylindrical in cross section, while the roller 8 is substantially polygonal in cross section, having a series of sides 9 which are substantially flat and intersect to form apexes 11. As the rolls 7 and 8 are rotated in the 30 directions indicated by the arrows in Fig. 3, the strip 2 will be formed to substantially the shape illustrated in Fig. 2, and if desired by suitably shaping the roll 8 the exact shape of Fig. 2 could be achieved.

The action of the rolls 7 and 8 will result in an increase in the length of the strip and thus the weight per fixed length of the formed strip will be correspondingly reduced to that of the original strip. These results can be readily established mathematically, for example, assuming the center line distance between the tubes 1 was

35 .5625 inch, the distance y .06 inch and the average thickness of the portion 6 and that of the unformed strip 2 to be .005 inch, with the intermediate portion 5 of minimum thickness being .0025 inch, the length of the formed strip would be approximately 25% greater than the original total length of the unformed strip. Likewise there may be a reduction in weight in the neighborhood of 20% per fin strip across the exchanger. It will be ap-

preciated that in present day heat exchange design, wherein minimum weight factors are stressed, a saving in weight of the above amount may be a very important design factor, particularly when no loss in efficiency accompanies the weight reduction. As the flanges 4 are formed from the thicker portion 6, a very efficient heat transfer is effected between the fin structure and the tube, as well as providing a stronger and more durable assembly. Likewise, the working of the metal tends to provide improved engagement between the tubes and fins.

In fabricating the fin structure in the manner illustrated in Fig. 3, the maximum distance or space between the rolls 7 and 8 would normally be somewhat less than the minimum thickness of the original strip in accordance with commercial tolerances to insure a uniform product.

Figs. 4 and 5 illustrate the method of forming the fin material by means of a pair of rolls the axes of which extend parallel to the longitudinal axis of the strip, the roller 7' being cylindrical, with the roller 8' having a longitudinal sectional shape corresponding to the shape of the top surface of the formed fin as illustrated in Figs. 1, 2, and 3. With this method, the strip S' may be of lesser thickness than the formed thickness of the portions 6 and greater than the minimum thickness of the intermediate portion 5 of the formed strip. Thus the roll 8' is provided with spaced cylindrical portions 12 of minimum diameter corresponding in axial width to the width of the portions 6 of the fin structure, having intersecting conical portions 13 extending therefrom, the portions 13 increasing in diameter from the portions 12 with adjacent portions 13 intersecting on a circumferential line 14 corresponding to the intermediate portion 5 of the least thickness of the fin structure.

It is believed apparent from the above description that an equivalent fin structure is provided by either of the methods illustrated in Fig. 3 or 5, the main distinction between the two being that in the former the metal is stretched and the area thereby increased, whereas in the latter the material is transferred by pressure from an area of minimum thickness to the area of maximum thickness.

It will be noted from the above description that I have disclosed a fin structure which may be formed from strip or sheet material and formed by a novel method to provide a tapered fin effect together with improved characteristics and with a corresponding reduction in weight and cost of material of a heat exchanger utilizing the same. It will be particularly noted that the fin structure may be fabricated by a comparatively simple yet highly efficient method of forming the fin elements.

Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

1. The method of forming a heat exchanger including a secondary surface heat exchange element, which comprises the following steps: subjecting thin flat sheet metal stock of predetermined substantially uniform thickness to forming pressure distributed over a sheet face in a predetermined pattern of non-uniform pressures between opposite faces of said element to effect a flowing of metal from certain areas to laterally adjacent areas to produce an element of a heat exchanger providing integrally connected relatively thick portions at longitudinally spaced points and relatively thin portions intermediate said points, punching flanged openings in the relatively thick portions for operatively connecting primary tubular heat exchange elements within the flanged openings at the thick portions, and said relatively thin portions providing fin structures

tapering outwardly with respect to the contiguous primary tubular heat exchange elements.

2. The method of forming a secondary surface heat exchange element for a heat exchanger, which comprises the steps: subjecting thin flat sheet metal stock of a predetermined thickness to forming pressures distributed over a face of the sheet in a predetermined pattern of nonuniform pressures between opposite faces of said element to effect a flowing of metal from longitudinally spaced portions which are thereby reduced in thickness providing thin portions, to adjacent intermediate portions which are thereby increased in thickness providing thick portions, as a result of such forming action, each of such portions extending substantially from one edge of the sheet to the opposite edge thereof, the length of the element remaining substantially constant during the forming action, punching flanged openings in the relatively thick portions for operatively connecting primary tubular heat exchange elements at the relatively thick portions, and said relatively thin portions providing fin structures tapering outwardly with respect to the contiguous flanged openings in the thick portions.

3. The method of forming a heat exchanger including a secondary surface heat exchange element, which comprises the steps: subjecting thin flat sheet metal stock of substantially uniform thickness to forming pressures resulting from engagement of said stock with a forming element having a non-planar sheet-engaging surface whereby the forming pressures are distributed across the face of the sheet in a predetermined pattern of non-uniform pressures along said element to effect a flowing of metal from certain elongated areas to adjacent substantially parallel extending areas to produce an element of a heat exchanger having relatively thick portions at points to be operatively connected to primary tubular heat exchange elements and relatively thin portions intermediate such points with such portions being disposed in generally parallel relation, forming flanged openings in the relatively thick portions for operatively connecting the primary tubular heat exchange elements, and said relatively thin portions providing fin structures tapering outwardly with respect to the contiguous primary tubular heat exchange elements affixed within the flanged openings in the relatively thick portions.

4. The method of forming a secondary surface heat exchange element for a heat exchanger, which comprises the steps: subjecting thin flat sheet metal stock of predetermined thickness to forming pressures distributed across a face of said sheet in a predetermined pattern of non-uniform pressures on said element to effect a compression of said metal and a longitudinal flowing thereof from certain areas to longitudinally adjacent areas to produce an element of a heat exchanger having alternate relatively thick and thin portions, each of which extends substantially from one edge of the element to the opposite edge thereof with relatively thick portions at points to be operatively connected to primary tubular heat exchange elements and relatively thin portions intermediate such points, the longitudinal length of the element being extended as a result of such forming action, punching flanged openings in the relatively thick portions for operatively connecting the primary tubular heat exchange elements, and said relatively thin portions providing fin structures tapering outwardly with respect to the relatively thick portions providing a maximum heat transfer with a minimum of metal in the secondary surface heat exchange element.

5. The method of forming a secondary surface heat exchange element of a heat exchanger, which comprises the steps: subjecting thin flat sheet metal stock of predetermined thickness to forming pressures of a pair of cooperable spaced rolls having parallel axes, at least one of which varies in diameter along its axis whereby such forming pressures are distributed across a face of the sheet in a predetermined pattern of non-uniform pres-

sures between opposed faces of said element to effect a flowing of metal from portions spaced in an axial direction which are thereby reduced in thickness providing relatively thin portions, to adjacent substantially parallelly extending intermediate portions which are thereby increased in thickness providing relatively thick portions for increasing the strength of said heat exchange element, as a result of such forming action, the length of the element remaining substantially constant during the forming action forming flanged openings in 10 said relatively thick portions for affixing primary heat exchange elements thereto in heat exchange relationship, and said relatively thin portions providing fin structures tapering outwardly with respect to the relatively thick portions increasing the heat conductivity of said secondary 15 surface heat exchange element.
